WALL RACK OR SIMILAR ARTICLE

Carl E. Gingher, 304-328 Depot St., Scranton, Pa.

Filed Sept. 11, 1964, Ser. No. 81,680

Term of patent 14 years

(Cl. D33—8)

I claim:

The ornamental design for a wall rack or similar article, as shown and described.
